Gebhardt, P.A.

(57) **CLAIM**

The ornamental design for a handle for lawn and garden
tool, as shown and described.

DESCRIPTION

FIG. 1 is a top left perspective view of a handle for lawn and
garden tool in accordance with the claimed design;

FIG. 2 is a bottom right perspective view of the design of
FIG. 1;

FIG. 3 is a top plan view of the design of FIG. 1;

FIG. 4 is a bottom plan view of the design of FIG. 1;

FIG. 5 is a right side elevation view of the design of FIG. 1;

FIG. 6 is a left side elevation view of the design of FIG. 1;

FIG. 7 is a rear elevation view of the design of FIG. 1; and,

FIG. 8 is a front elevation view of the design of FIG. 1.

The dash-dash broken lines in the figures (e.g., including
portions depicting unclaimed parts of the lawn and garden
tool, the attached battery, and the longitudinal seam lines)
represent environment and form no part of the claimed
design.

The dot-dash broken lines in the figures immediately adja-
cent the solid lines (and inside the circular tube in FIG. 8)
represent a boundary between claimed and unclaimed sub-
ject matter and form no part of the claimed design.

The labels used herein to describe orientation (e.g., top,
bottom, left, right) are merely for reference and are not
intended to limit the interpretation of the design.

Applicant reserves the right to convert: a portion or portions
of any of the broken lines to solid lines such that the features
described by those lines then form a part of the claimed
design; and/or a portion or portions of any of the solid lines
to broken lines such that the features described by those lines
no longer form part of the claimed design.

1 Claim, 7 Drawing Sheets
